Patented Sept. 7, 1976

241,346

FISHING LURE

Robert G. Carver, Athens, La.
(P.O. Box 741, Minden, La. 71055)

Filed Apr. 7, 1975, Ser. No. 565,586

Term of patent 14 years

Int. Cl. D22—05

U.S. Cl. D22—27

FIG. 1

FIG. 2

FIG. 3

FIG. 4

FIG. 1 is a top plan view of the fishing lure, showing my new design;

FIG. 2 is a side elevational view thereof;

FIG. 3 is an enlarged cross-sectional view taken along the line 3—3 in FIG. 1; and

FIG. 4 is an enlarged cross-sectional view taken along the line 4—4 in FIG. 1.

I claim:

The ornamental design for fishing lure, substantially as shown.
